UNITED STATES PATENT OFFICE.

JAMES HANNA, OF BALTIMORE, MARYLAND, ASSIGNOR OF ONE-HALF TO CLARENCE D. PRUDEN, OF BALTIMORE, MARYLAND.

BILLIARD-CUE.

1,092,100.

Specification of Letters Patent. Patented Mar. 31, 1914.

Application filed July 10, 1913. Serial No. 778,234.

To all whom it may concern:

Be it known that I, JAMES HANNA, a citizen of the United States, residing at Baltimore, in the State of Maryland, have invented certain new and useful Improvements in Billiard-Cues, of which the following is a specification.

This invention relates to an improvement in billiard cues.

It is desirable that provision be made to readily remove the elastic tip of a billiard cue and to quickly replace it by securing another tip in position. It is also desirable that the means for securing the tip shall be such as to prevent all slight twisting or partial-turning movement of the tip on its seat at the end of the cue.

To accomplish the objects of this invention I provide two separate sheet-metal levers of novel construction that will mechanically connect with the tip and frictionally connect with the cue.

The improved means constituting the present invention is illustrated in the accompanying drawing in which,

Figure 1 is a longitudinal section of the improved billiard cue in which the tip fastener is shown in normal position. Fig. 2 is a view of the three parts separately shown comprising a billiard cue according to this invention,—the tip and cue being shown in section and the tip-fastening shown in side view. Fig. 3 is a perspective view of one of the levers of the fastener device. Fig. 4 is a cross-section of the cue on the line 4—4 of Fig. 1. Fig. 5 is a view of the bottom side of the tip.

Referring to the drawing the wood cue, 1, has a longitudinal center bore, 2, at its small end. The elastic tip, 3, is made of any well known material commonly used for tips, and has a base, 4, of harder material; an elongated slot, 5, is formed in the said base part of the tip, and a slight recess, 6, is in the elastic part coincident with the slot. The fastening device is entirely separate from the tip, and consists of two levers, 7, 8, of special construction. Each lever has a short end, 10, and a longer end, 13; the short end is flat and has a breadth equal to the length of the diametrical slot, 5, in the tip so that when inserting it will fill the slot, and the extremity of said flat end is provided with a row of teeth, 11, that project laterally at the outer side. The long end,

13, of each lever is straight longitudinally and in cross-section is concavo-convex, as seen in Figs. 3 and 4; this cross-section removes the elasticity and makes the straight end, 13, stiff. Each lever also has a narrow elastic shank, 12, which connects between the broad flat end, 10, and the longer end, 13, and at each connecting point the said shank forms a bend,—the bend, 9, where the shank connects with the broad flat end 60 serves as a fulcrum, and the said fulcrum, 9, of one lever contacts with the fulcrum of the other lever.

It will be understood the toothed extremities, 11, of both levers are to enter the slot, 70 5, in the base of the tip. By reference to Fig. 2 it will be seen the broad flat ends, 10, of the two levers are in close contact for their entire length, this being the position they will have when the said toothed extremities have been entered through the slot, 5, and the teeth, 11, are in the slight recess, 6, above the slot. In the position now described both bends, 9, of said levers are in contact with each other, and the opposite 80 ends, 13, of the two levers diverge from each other, or spread apart. These two spread-apart ends, seen in Fig. 2, may be compressed or brought together and then inserted into the center bore, 2, of the wood 85 cue. The effect of bringing the levers ends, 13, together, the bends, 9, serving as a fulcrum, is to spread or separate the two broad flat ends, 10, and cause their teeth, 11, to engage above the hard base, 4, of the tip, 90 as shown in Fig. 1, and also cause said two broad ends, 10, to exert pressure in opposite direction against the two long sides of the slot in the tip. The hold of the teeth prevents the tip from disconnecting from the 95 cue, and the pressure in opposite directions on the long sides of the tip-slot prevents any twisting or partial-turning movement of the tip.

When a tip is worn out, it may be removed by forcefully pulling the levers out of the bore. A new tip may be applied and the same levers used to fasten it.

Having thus described my invention what I claim and desire to secure by Letters Patent is:

A billiard cue having in combination a wood cue provided at its end with a longitudinal bore; a pad or tip having an elongated slot extending diametrically across its 110

base and seated directly on the end of the cue; and two levers entirely separate from the tip each lever having a flat end whose breadth equals the length of said slot in the tip and the flat end provided with a row of lateral teeth, each lever also having a longer straight end which is stiffened by a longitudinal concave depression, and a shank narrower than either of said ends and connecting the broad flat end and the said longer

stiffened end—the broad flat ends of said levers being expanded and pressing against the long sides of the tip-slot.

In testimony whereof I affix my signature in presence of two witnesses.

JAMES HANNA.
